ARTICLE CLUTCHING ATTACHMENT FOR
A MOBILE JACK

Harold S. Church, 464 Tyler St., Monterey, Calif.

Filed Apr. 16, 1957, Ser. No. 653,186

4 Claims. (Cl. 269—144)

This invention relates to an article supporting and clamping device, the major object being to provide a device of this general kind particularly designed to handle and clamp heavy objects, such as motor vehicle transmissions, differentials, and the like, and which is arranged to be mounted on a mobile jack, or in a stationary or turnable position on a work bench.

A further object of the invention is to provide a device, for the purpose, which includes an article supporting table, and article engaging and clamping elements mounted on and upstanding from the table; said elements being independently adjustable both vertically and horizontally to conform to the contour, shape, and size of any article supported on such table.

By means of this device odd shaped articles which are not stable or self-supporting when in certain positions, may be held in any desired position relative to the table so that the article may be worked on while on the table, and the latter may be rotated, tilted, or moved up and down or from place to place, without the article shifting its position on the table.

The device is therefore admirably adapted to be mounted on a mobile jack for the engagement and removal of a part (such as the transmission unit) from a motor vehicle, and which unit—while still on the table—may then be worked on in any manner necessary, and finally replaced in its proper position on the vehicle.

Another object of this invention is to provide an article clutching attachment for a mobile jack which is designed for ease and economy of manufacture.

It is also an object of the invention to provide a practical, reliable, and durable article clutching attachment for a mobile jack.

These objects are accomplished by means of such structure and relative arrangement of parts as will fully appear by a perusal of the following specification and claims.

In the drawings:

Fig. 1 is a side elevation of the device as in operation, or as engaged with a motor vehicle part, and shown as mounted on a conventional mobile jack.

Fig. 2 is a transverse section on line 2—2 of Fig. 1.

Fig. 3 is a fragmentary enlarged vertical section on line 3—3 of Fig. 2, showing the position of a clamping arm and the corresponding compressor unit when the arm-mounted pin is first engaged with a part to be clamped.

Fig. 4 is a similar view, but shows the final clamping position of the arm and compressor unit.

Fig. 5 is an end view of a compressor unit as detached from the table and with the arm-pressing rod removed from the unit.

Referring now more particularly to the drawings, and to the characters of reference marked thereon, the device comprises a flat rectangular base 1 of any suitable size. This base may rest directly on a work bench or on a bench-supported turntable, but is here shown as being removably supported on the top platform 2 of a conven-

2

tional mobile jack, a portion of which is shown at 3 (see Fig. 1). The base is secured on the platform 2 by suitably spaced bolts 4.

Longitudinal open-topped channels 5 are formed as a unit with the base 1 on opposite sides thereof; flanges 6 along the sides of the channels at the top thereof overhanging the channel areas. The channel walls are rigid and—together with base 1—form a work supporting table.

10 Each channel forms a guide and locating means for a pair of separate work-engaging and clamping units, and since all such units are of identical form and construction, a description of one unit will suffice for all.

Each unit comprises a rigid arm 7 upstanding from 15 within a channel between the flanges 6, and mounted at its lower end on a block-like, generally rectangular foot 8 projecting under the flanges 6 and slidably guided by the channel against lateral deflection. The foot, however, is arranged, as shown at 9, to allow of a certain amount 20 of tilting of the arm in a direction lengthwise of the channel and toward the opposed arm.

The arm 7 above the channel is of channel form, as shown at 10; the open side of such channel facing one 25 end of the table. A block 11 is slidable up and down in channel 10, being retained at any desired position along the arm by means of a transverse pin 12 projecting through the block 11 and through any desired pair of rows of holes 13 provided in the arm 7 lengthwise thereof.

The pin 12 is positioned near the upper end of the 30 block, and a sharp pointed, hardened pin 14 projects horizontally from the front face of the block 11 at its lower end in the direction toward which channel 10 faces. A smaller pin 15 projects from the block 11 in alignment with pin 14, through a hole 16 in the back 35 or bottom of the channel 10; such hole 16 being one of a row of holes spaced apart the same as the spacing of holes 13.

Mounted in block 11—and projecting from the back face thereof above the pin 15, but below the level of 40 pin 12—is a spring-urged pin 17, which, at its outer end, engages the back wall of channel 10, and acts—if unrestrained—to swing block 11 about pin 12 so that pin 14 is then disposed at a slight upward slope relative to arm 7, as shown in Fig. 3.

45 A compressor or pressure unit, which also constitutes a push-pull unit, is detachably used with each arm 7. Such unit comprises a supporting frame 18 consisting of a pair of upstanding, spaced, strap-like members 19 rigidly connected together along the lower portion of their side edges by a cross strap 20, and which strap forms the back of a hook 21 arranged to engage over the upstanding end wall 22 of channel 5, as shown in Fig. 3.

50 A lever 23, which comprises spaced arms 24 connected at their lower end by a depending actuating handle 25, is 55 disposed between—and pivotally connected, as at 26, at its upper end to—the members 19 of frame 18.

A gripper element G is disposed between arms 24 and is mounted on said arms for free swinging movement by a transverse pivot pin 27. Below pin 27, element G is 60 formed with a sharp-edged hole 28 projecting therethrough at right angles to pin 27.

A rod 29 slidably and freely projects through hole 28; said rod at one end being formed with a small head 30 adapted to engage in a socket 31 in the back of arm 7, and which socket may be one of the adjacent holes 16. The rod 29 adjacent its other end is formed with a short portion 32 of reduced size, adapted to engage in a cradle 33 of corresponding size upstanding from the back end of the arm foot 8. The purpose of this feature 70 of construction will be seen later.

A normally slack helical spring 34 projects forwardly (or toward arm 7) from the adjacent side of element

G, and is secured to the same, as at 35. A similar spring 36 projects rearwardly from—and is secured to—the back face of element G; both springs being of a size to freely surround rod 29, while at the same time they are not connected thereto.

In order that any arm 7 may be removed from association with the table at any time, the flanges 6—intermediate their ends—are cut away, as at 37, for a length slightly greater than that of the foot 8, so that when the latter is alined with the cutaway 37 said foot may be lifted straight up and withdrawn from the channel.

In operation, the pairs of arms are first retracted along channels 5 as far as possible, in order to allow the article or piece of work W to be handled to be received on—and supported by—the table without interference. The table is set relative to the work so that the latter, if elongated, extends crosswise of the table. The compressor or push-pull units are also removed from the table at this time.

The work having been seated on the table, the different arms—related to each channel—are on opposite sides of the work. The arms are then slid along the channels until the pins 14 engage the work; said pins being first adjusted vertically so that they occupy proper and desirable work-engaging positions. The pins 15 are thereafter struck a light hammer blow by the operator so that the points of pins 14 indent the work and provide non-slip engagement therewith.

The frames 18 are then hooked into place on the table, and the rods 29 are slid forward through the respective elements G so that the heads 30 engage in suitable sockets 31; the levers 23 being held in a retracted position while this is being done, as shown in Fig. 3.

Pressure is then exerted on spring 34 by a finger or hand tool in the direction indicated at P in Fig. 4, so as to compress the spring and force element G into tilted and wedging engagement with the rod 29; said rod being held at the time against rearward movement.

While holding the spring compressed, the handle 25 is pressed forward to swing the lever 23 into frame 18. This causes the binding action of the gripping element on the rod 29 to be increased, and the latter to be pressingly advanced against the work.

Due to the loose fit of the foot 8 in channel 5, the arm 7 is tilted slightly toward the work by the rod pressure, and the foot 8 is likewise tilted and becomes wedged against longitudinal movement in the channel 5. This causes the pin 14 to press firmly against the work, and also causes the work to be forced downwardly against the table, since the tilting of the arm is accompanied by a downward movement of the pointed and work-engaging end of the pin.

With the opposite arm being similarly engaged by a push-pull or pressure unit, the work is held firmly against the table and cannot slip, turn, or tilt relative thereto. The table—with the work thus gripped or clamped thereon—may be turned or tilted as may be necessary when operating on the work piece, without the latter shifting its position on the table.

When the work is to be unclamped and removed from the table, the spring 36 of each push-pull unit is first compressed to release the element G from its gripping engagement with rod 29, so that the latter may be pulled through element G and disengaged from the arm from said element and the springs.

The rod is then reinserted in a reversed position, and the reduced portion 32 engaged with the cradle 33, as shown in dotted lines in Fig. 4. The spring 36 is again compressed sufficiently to cause the rod 29 to be clamped in element G, and the handle 25 is then grasped and the lever 23 swung out from the frame 18. This will cause the rod 29 to pull back on the foot 8, breaking the clamping hold of said foot in the guide channel 5 so as to disengage the pin 14 on the arm from the work.

The rods 29 are of sufficient length to enable them to engage the related arms 7 irrespective of the position the arms may occupy along the table and relative to the fixed-position or push-pull compressor units.

From the foregoing description it will be readily seen that there has been produced such a device as will substantially fulfill the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. A work holding device comprising a table on which to support a piece of work, arms upstanding from the table in spaced opposed relation to each other lengthwise of the table so as to be on opposite sides of the work, elements mounted on and projecting from the arms toward each other for engagement with the work, means mounting the arms on the table for tilting movement toward and from each other, and a pressure unit for each arm mounted on the table beyond and in alinement with the related arm; said unit comprising an upstanding frame rigid with the table, a hand lever swung at one end in the frame on a transverse horizontal axis for fore and aft movement relative to the table and arm, a gripping element swung in the lever intermediate its ends on a transverse axis and having a hole therethrough at right angles to said axis, and a rod normally freely slidable through and adapted to be tilted in the hole and arranged at one end to engage the arm at a selected distance above the table; said rod being adapted to be gripped by the element upon tilting of the latter relative to the rod.

2. A work holding device comprising a table on which to support a piece of work, arms mounted on and upstanding from the table in spaced and opposed relation to each other so as to be on opposite sides of such work, a block engaging each arm, a pin rigid with and projecting from the block toward the opposed arm and terminating in a point on its end furthest from the block to engage a work piece disposed between the arms, a pivot pin disposed transversely of and above the first named pin mounting the block on the arm for limited swinging movement, and a pin-like element projecting from the back of the block and rigid therewith in substantially axial alinement with the work engaging pin and exposed at its outer end for engagement with a hammer or the like.

3. A work holding device comprising a table on which to support a piece of work, arms mounted on and upstanding from the table in spaced and opposed relation to each other so as to be on opposite sides of such work, a block engaging each arm, a pin rigid with and projecting from the block toward the opposed arm and terminating in a point on its end furthest from the block to engage a work piece disposed between the arms, a pivot pin disposed transversely of and above the first named pin mounting the block on the arm for limited swinging movement, and a spring-pressed element mounted in the block and yieldably engaging the arm below the pivot pin to normally swing the block on said pivot pin and dispose the work engaging pin at an initial upward slope relative to the arm.

4. A work holding device comprising a table on which to support a piece of work, arms upstanding from the table in spaced opposed relation to each other lengthwise of the table so as to be on opposite sides of the work, elements mounted on and projecting from the arms toward each other for engagement with the work, enlarged feet on the lower ends of the arms, a channel in the table in which the feet are slidable and arranged to

allow of limited tilting of the arms toward and from each other, and a push-pull unit for each arm mounted on the table beyond and in alignment with each arm; such unit comprising an upstanding frame rigid with the table, a hand lever swung at one end in the frame on an axis transversely of the channel for fore and aft movement relative to the arm, a gripping element mounted in the lever intermediate its ends, a rod removably engaged by the element, and an upwardly facing cradle on the foot between the arm and the frame; the rod at one end being arranged to engage the arm at a selected distance above the table and to push on and tilt the arm and foot in a direction away from the frame upon swinging of the lever toward the arm, said rod at its other end being formed with a recessed portion to engage and seat in the cradle upon the rod being reversed in the gripping element, and so that the foot will be pulled upon swinging movement of the lever away from the arm.
